UNITED STATES PATENT OFFICE

2,646,032

APPARATUS FOR PRODUCING SMOKE

Frederick William Horn Watson, Glasgow, Scotland, assignor to The Mirrlees Watson Company Limited, Glasgow, Scotland, a company of Great Britain and Northern Ireland

Application June 13, 1950, Serial No. 167,900
In Great Britain June 23, 1949

1 Claim. (Cl. 126—59.5)

1

This invention relates to a smoke-producing apparatus for use in the curing industry.

An apparatus according to the invention is adapted to burn sawdust, peat or other form of fuel, which is fed to the burner apparatus by means of an "underfeed" or other mechanical stoker.

The apparatus includes a casing formed at the top with an outlet for the smoke and accommodating within its lower portion a retort structure upwardly through which the fuel is fed by the stoker.

Surrounding the retort structure is a perforated grate or liveplate upon which the fuel is spread by a rotary spreader arranged immediately above the grate.

Fitted around the top of the retort structure is a rising ring which causes the incoming fuel to rise to the top of the fuel bed before admixture of the fuel with combustion air and ignition take place, resulting, in effect, in "overfeed" of the grate.

The fuel spreader may include blades or arms carried by an upright shaft which may be gear and chain driven from an extension of a shaft of the stoker.

A small power-driven variable-output pump may be provided for the purpose of supplying a metered quantity of water to the fuel entering the retort, so that the correct conditions may be maintained for the maximum production of smoke.

A smoke-producing apparatus according to the invention is illustrated in the accompanying drawings in which Fig. 1 is a vertical longitudinal section, and Fig. 2 is a part plan part horizontal section, of the apparatus. Fig. 2 is drawn to a larger scale than Fig. 1.

Referring to the drawings, the smoke-producing apparatus shown is adapted to burn sawdust, peat or other form of fuel, which is fed to the apparatus by means of an "underfeed" or other mechanical stoker part of which is indicated generally at 10.

The apparatus includes an outer cylindrical casing 11 formed at the top with an outlet 12 for the smoke and accommodating within its lower portion a centrally disposed upwardly divergent retort structure 13 upwardly through which the fuel is fed by the worm 15 or the like of the stoker 10. The rate of feed of the stoker may be regulated as desired while the stoker is operating.

Surrounding the retort structure 13 is a perforated grate or liveplate 16 upon which the fuel is spread by a multi-bladed rotary spreader 17 arranged immediately above the grate.

2

Fitted around the top of the retort structure 13 is a rising ring 18 which causes the incoming fuel to rise to the top of the fuel bed at 19 before admixture of the fuel with combustion air and ignition take place, resulting, in effect, in "overfeed" of the grate.

The perforations in the grate or liveplate 16 are constituted by small air inlet orifices 20 communicating with an air chamber 21 below the grate. Air for combustion may be controlled at the suction side and at the delivery side of an air supply fan.

The fuel spreader blades or arms 17 are carried by an upright shaft 22 which is gear and chain driven from an extension 23 of the worm shaft 24 of the stoker.

A small power-driven variable-output pump 25 is provided for the purpose of supplying through a pipe connection 26 a metered quantity of water to the fuel entering the retort 13 so that the correct conditions may be maintained for the maximum production of smoke. The amount of water supplied is proportional to the quantity of fuel being fed to the fire, the proportion being regulatable by the operator.

A smoke filter 27 may be provided within the upper portion of the casing 11.

The elements of combustion are all under control.

I claim:

A smoke-producing apparatus for use in the curing industry, including an upright casing provided with an outlet for smoke at the top, a retort structure located centrally in the lower portion of the casing and having a diverging wall terminating in a fuel outlet opening facing upwardly in the casing, a laterally-extending worm for feeding fuel into the lower portion of and upwardly through the retort structure, a perforated laterally-extending grate on a level with and surrounding the outlet portion of the retort structure for supporting a fuel bed, a rising ring fitted around the outlet opening at the top of the retort structure and adapted to cause fuel fed upwardly in the retort structure to move upwardly to a level above the said grate and be deposited on top of the fuel bed on the grate, a rotary fuel spreader immediately above the ring including an upright shaft axially arranged with respect to the ring and laterally-extending blades carried on the lower end portion of the shaft and extending radially directly over the top of the ring and over the grate and spaced a substantial distance above the grate, said blades being adapted to spread the fuel delivered through and to the top of the ring over the surface of the fuel bed on the grate,

said blades having operative edges located below the level of the top of the rising ring, means interconnected with the worm and with the upright shaft above the blades for driving the shaft and the blades, a smoke filter in the upper portion of the casing above said upright shaft, and means including a power-driven variable-output pump for supplying a metered quantity of water to the fuel being fed to the retort structure by the worm.

FREDERICK WILLIAM HORN WATSON.
